Letter, Patient d^o 2891-Dated May 16-1866.

Design for the Plates of a Parlor Stove.

The schedules referred to in these letters patent and making part of the same.

Scalp when it may occur:

Be it known that I, Samuel H. Kress, of the City and County of Albany, and State of New York, have invented, or produced, a new and original design for plates for a photographic camera, and I do hereby declare that the following is a full and exact description of the same, reference being made to the accompanying photographs.

A represents the design for the heart-plate,

C end of stove;

D fancy top of

All combined together forming the plates for a Panorama,
"The Palm."

Claim is now and desire to secure by Letters
design for plates of fastener to as shown and described.
